UNITED STATES PATENT OFFICE.

JAMES E. ERSKINE, OF JACKSONVILLE, FLORIDA.

DESIGN FOR A STEP PLATE FOR AUTOMOBILE RUNNING BOARDS.

Application filed May 11, 1925. Serial No. 13,416. Term of patent 7 years.

To all whom it may concern:

Be it known that I, JAMES E. ERSKINE, a citizen of the United States, residing at No. 723 Park Street, Jacksonville, in the county of Duval and State of Florida, have invented a new, original, and ornamental Design for Step Plates for Automobile Running Boards, of which the following is a specification, reference being had to the

accompanying drawing, forming part thereof.

The figure is a perspective view of a step plate for automobile running boards, showing my new design.

I claim:

The ornamental design for a step plate for automobile running boards, as shown.

JAMES E. ERSKINE.
